LOCOMOTIVE FUEL CONVEYER

Henry E. Lippert, Pittsburgh, Pa.

Application April 22, 1935, Serial No. 17,607
Renewed August 27, 1938

19 Claims. (Cl. 198—15)

This invention relates to fuel conveyers and stokers, and particularly to the conduit system and fuel impelling means thereof.

An object of the present invention is to arrange or dispose the conduits and the fuel impelling means in novel and improved relation with each other. Another object is the provision of this improved relation of conveyer parts within a locomotive.

10 It is a further object of the invention to provide in a locomotive, an elevator or riser conduit, a delivery conduit and a helical screw within the delivery conduit, and to arrange these parts with respect to one another so that fuel can be forced freely and easily through the riser conduit by the screw.

Stated specifically, the improvement consists in providing in a locomotive, a riser conduit of novel formation arranged to direct fuel to a position for its distribution over the firebed, a delivery conduit and a helical screw solely within the delivery conduit arranged to force fuel through the riser conduit, and in disposing the conduits and screw in an improved relation with each other so that the screw can discharge the fuel laterally from its underside from one conduit into the other.

Other objects, advantages and details of the invention will appear from a reading of the following description, taken in connection with the accompanying drawings, forming a part hereof, in which:

Fig. 1 is a vertical longitudinal sectional view of a rear portion of a locomotive and a forward portion of a tender, with the improved conveyer applied thereto. Parts of the conveyer are broken away and removed.

Fig. 2 is a transverse section taken on line 2—2 of Fig. 1.

40 Fig. 3 is a vertical transverse sectional view taken on line 3—3 of Fig. 1.

Fig. 4 is a longitudinal vertical section taken on line 4—4 of Fig. 3.

45 Fig. 5 is a transverse sectional view taken on line 5—5 of Fig. 1.

Fig. 6 is a vertical longitudinal central section of the locomotive backhead with the riser conduit of the conveyer mounted thereon. The upper 50 portion of the riser conduit is shown in section and the lower portion thereof in elevation, the conveyer delivery conduit being removed.

Fig. 7 is a transverse sectional view taken on irregular line 7—7 of Fig. 6 with the delivery 55 conduit replaced.

Fig. 8 is a transverse section taken on line 8—8 of Fig. 7 on a reduced scale.

Fig. 9 is a horizontal transverse sectional view taken on line 9—9 of Fig. 7, and

Fig. 10 is a vertical section taken on line 10—10 of Fig. 9.

Referring to the drawings, a locomotive designated generally by the letter L is coupled at 10 in the conventional manner to a tender T. The locomotive has a firebox 11 provided with grates 12, a backhead 13 having a firing opening 14 therein, a cab 15 provided with a cab deck 16 below the elevation of the firing opening, and a frame 17. The tender has a fuel bin or bunker 18, a deck 19 extending beneath the fuel bunker, 15 a frame 20, and a compartment 21 between the bunker 18 and tender frame 20 for receiving the rear end of the fuel conveyer.

The conveyer comprises, generally speaking, a transfer portion extending from beneath the 20 bunker 18 to a point adjacent the backhead 13, and a combined firedoor casing and riser conduit in the locomotive. The transfer portion comprises an upwardly open trough A mounted on the tender in compartment 21, and a tubular 25 delivery conduit D. The lower part of the combined firedoor casing and riser conduit forms the conveyer riser conduit R, and the upper part thereof forms the firedoor casing F.

The center of trough A is arranged in the 30 vertical central plane of the tender. Mounted on each side of the trough approximately equidistant from the ends thereof is a roller 22 arranged to turn about a common transverse axis, and rest upon angle irons 23 attached to the side 35 walls of compartment 21. This supporting arrangement for the trough permits the latter to swing laterally about a vertical axis midway between the rollers, and also allows the trough to rock slightly in a vertical plane about the axis 40 of rollers 22 when the locomotive and tender pass over turn-tables and "cross-overs". A spring 24, composed of a pair of spring-steel plates, is secured to the tender frame 20 and arranged to slidably engage the underside of the trough to 45 maintain the latter in a horizontal position under normal operating conditions, should there be any tendency for the trough to tilt. If desired, a coil spring inserted between the forward end of the trough and the tender frame may be used to 50 accomplish the same purpose.

To prevent loss of fuel between the tender deck 19 and trough A, a sealing frame 25, rectangular in shape and formed of angle irons, is held in contact with the underside of the tender deck 55

by means of adjustable screws 26 on the trough. The frame 25 extends downwardly into trough A to move in a horizontal plane therewith.

5 A tubular extension 27 on the forward end of the trough is provided with an enlargement 28 on which the rear end of the delivery conduit D is seated. Trough A and delivery conduit D are pivotally connected together in end-to-end relation by means of a clamp 29 which engages projections 30 and 31 on the top and bottom faces, respectively, of the enlargement 28. The outer surface of the enlargement 28 and the inner surface of the portion of the delivery conduit D overlapping this enlargement are substantially square in vertical transverse section (Fig. 2) and arcuate in horizontal transverse section (Fig. 5). The pivotal connection between trough A and conduit D prevents movement of one with respect to the other in a vertical plane, but permits 10 the delivery conduit to swing laterally with reference to the trough about the approximately vertical axis of projections 30 and 31.

15 The delivery conduit D slopes upwardly from beneath the tender deck 19 to the cab deck 16. The rear end of this conduit is arranged in the vertical central plane of the tender, and its forward end is disposed to the left side of the vertical central plane of the locomotive. The conduit D is substantially cylindrical in shape, and comprises a forward short section 32 and a rear section 33 rigidly secured together. The inner surface of forward section 32 is of greater diameter than the inner surface of rear section 33.

20 A ball element or enlargement 35, which constitutes one part of a ball and socket joint between the delivery conduit D and the riser conduit R, is formed on the forward section 32 and received by a spherical seat or flange 36 formed on the lower end of the riser conduit. Conduits D and R are flexibly connected together by means of a ball joint clamp 37. A wall 38 closes the front end of the delivery conduit, and a fuel outlet aperture or opening 39 in the lower portion of the right side wall of this conduit is spaced slightly rearward of the front wall 38. The outlet openings 39 and a fuel inlet aperture or opening 40 in the lower end of the riser conduit register with each other to provide communication between the lower half of the conduit D and the conduit R. The delivery conduit D opens laterally with respect to its axis through the spherical surface of enlargement 35, and the riser conduit R opens laterally on the left side of the vertical central plane of the locomotive through the spherical surface of flange 36. The forward end 25 of the delivery conduit opens at its side toward one side of the locomotive, and the lower end of the riser conduit opens toward the opposite side of the locomotive. Conduits D and R may be said to be disposed in side-to-end relation with each other, since the delivery conduit communicates through a side wall thereof with the lower end of the riser conduit.

25 The riser conduit R curves laterally, upwardly and forwardly from the conduit D to the firing opening 14. The forward and rearward walls 41 and 42, respectively, of the riser conduit curve forwardly, and the side wall 43 opposite the inlet opening 40, curves downwardly and laterally to the delivery conduit. The side wall 43 of the 30 riser conduit forms a laterally and upwardly extending curved continuation of the wall of the delivery conduit. The riser conduit at its upper end opens into the firedoor casing F, and extends an equal distance on each side of the vertical cen-

tral plane of the locomotive and the firing opening 14. The combined firedoor casing and riser conduit is rigidly secured adjacent the firing opening to the backhead 13 by studs 44, and is further supported by means of a bracket 45 on the lower end of the backhead.

35 The firedoor casing F extends around the sides and top of the firing opening 14, and carries a firedoor 46. A fuel distributing plate 47 extends through the firing opening, and is fixed on a shaft 48 journalled in the firedoor casing. The forward end of the distributing plate can be raised or lowered, according to the condition of the fire, by means of a set screw 49 arranged to engage an arm 50 on the shaft 48. A distributor head 51, 40 rearward of the upwardly open end of the riser conduit, is secured to the casing F by cap screws 52. Blasts of pressure fluid issue from jet holes 53 in the distributor head in a horizontal plane slightly above the top surface of plate 47 for discharging fuel into the firebox. A hinged guide 54 in each side wall of the firedoor casing F may be adjusted in fixed positions to narrow or widen the discharged stream of fuel and prevent the fuel from striking the walls of the firing opening 45 14.

45 A helical screw 55 in trough A is connected by a universal joint 56 to a helical screw 57 in the delivery conduit D. The trough screw 55 is fixed by pins 60 to a drive shaft 58 journalled in gear case 59. The screws 55 and 57 are rotated in the usual manner by a driving motor (not shown) operatively connected to a gear 61 fixed on drive shaft 58. The delivery conduit screw 57 extends across the outlet opening 39 substantially to the plane of the rearward or inside surface of front wall 38. The screw 55 is formed of a hub 62 and a right hand impelling helical thread or vane 63, and screw 57 has a hub 64 and a right hand main impelling helical vane 65. The vane 63 extends 50 throughout the length of the trough screw, and the vane 65 terminates opposite the center of outlet opening 39. A reverse vane or left hand impelling vane segment 66 is provided on the front end of screw 57. A right hand vane segment 67 and an additional left hand vane segment 68 are also formed on screw 57 opposite the outlet opening 39 in the conduit D. The left hand vane segments 66 and 68 are diametrically opposite each other, and right hand vane segment 67 is diametrically opposite the forward portion of right hand vane 65. The vane segments opposite the outlet opening 39 are of uniform radius, or stated in other words, the helical edges thereof are concentric with the axis of screw 57. The left hand vane segments 66 and 68 join, respectively, with right hand vane 65 and right hand vane segment 67 in a plane perpendicular to the axis of screw 57 through the center of outlet opening 39. The helical vane segments on the forward end of screw 57 are of greater diameter than the helical vane in the rear section 33 of the delivery conduit D. Telescopic joints in the conduit system and between the helical screws have been purposely eliminated. Since 55 the conduits and helical screws are not extensible, and the screw 55 is fixed with respect to longitudinal movement of the trough A by means of pins 60, the portion of screw 57 opposite the outlet opening 39 is fixed with reference to longitudinal movement of the opening.

60 In operation, fuel falls from the bunker 18 through an aperture 69 in the tender deck 19 into the trough A. The fuel is conveyed through the trough by helical screw 55 and through the deliv- 75

ery conduit D by the helical screw 57, and it is forced through the riser conduit R into the casting F by screw 57. The blasts of pressure fluid which issue from jet holes 53 in the distributor head 51 discharge fuel from the top of the upwardly advanced column of fuel onto the firebed on grates 12.

The helical screws 55 and 57 rotate normally in counter-clockwise direction, as indicated by the arrows in Fig. 7, so that screw 57 can discharge the fuel from its underside from the bottom half of delivery conduit D horizontally into the riser conduit R. The screw 57 rotates in such direction that the lower portion thereof at the delivery end moves toward the curved side wall 43. The left hand vane segments 66 and 68 cooperate with right hand vane 65 and right hand vane segment 67 to discharge or sweep the fuel laterally with reference to the axis of screw 57 and transversely of the locomotive through the outlet opening 39, and to force the fuel through the riser conduit.

The construction of helical screw 57, the forward end of the delivery conduit D, and the riser conduit R, and the relative position of these parts with one another provide a conveyer structure in which fuel can be forced freely, easily and in loose form through the riser conduit with less power than is required with similar devices, and without the aid of separate elevating mechanism in the riser conduit.

By the expression "reverse vane" used herein, the meaning intended to be conveyed is that such vane is wound on the hub of the screw in the opposite direction to that of the vane on the remaining portion of the hub.

The general arrangement of the above described fuel conveyer upon an intercoupled locomotive and tender, including the means for flexibly connecting the conveyer members to each other and the means for supporting the members upon the vehicles, has been made the subject matter of a divisional application, Serial No. 129,852 filed March 9, 1937, for Locomotive fuel conveyer.

I claim:

1. In a fuel conveyer for a locomotive having a firebox, a delivery conduit, a riser conduit arranged to direct fuel to a position for its distribution over the firebed in the firebox, said conduits communicating with each other, said riser conduit curving laterally and upwardly from the delivery conduit, and a helical screw within the delivery conduit constituting the sole means for impelling fuel therethrough and forcing it through the riser conduit, said screw having a reverse vane thereon at the communicating ends of said conduits and being arranged to normally rotate in such direction that the lower portion thereof at the delivery end moves toward the lower end of said riser conduit to discharge the fuel from its underside and transversely of its axis from one conduit into the other.

2. In a fuel conveyer for a locomotive having a firebox, a delivery conduit, a riser conduit arranged to direct fuel to a position for its distribution over the firebed in the firebox, said conduits communicating with each other, said riser conduit curving laterally and upwardly from the delivery conduit, and a helical screw within the delivery conduit constituting the sole means for impelling fuel therethrough and forcing it through the riser conduit, said screw having a reverse vane thereon at the communicating ends of said conduits and being arranged to discharge the fuel

from its underside and transversely of its axis from one conduit into the other, and the greater portion of the communicating opening between said conduits being disposed opposite the lower half of said screw.

3. In a fuel conveyer for a locomotive having a firebox, a delivery conduit, a riser conduit having a fuel inlet opening at its lower end and being arranged to direct fuel to a position for its distribution over the firebed in the firebox, said conduits communicating with each other, the side wall of the riser conduit opposite said inlet opening curving downwardly and laterally to the delivery conduit and forming a continuation of the wall of the delivery conduit, and a helical screw within the delivery conduit constituting the sole means for impelling fuel therethrough and forcing it through the riser conduit, said screw having a reverse vane disposed opposite said inlet opening and being arranged to normally rotate in such direction that the lower portion thereof at the delivery end moves toward the curved side wall.

4. In a fuel conveyer for a locomotive having a firebox, a delivery conduit, a riser conduit having a fuel inlet opening at its lower end and being arranged to direct fuel to a position for its distribution over the firebed in the firebox, said conduits being in communication with one another, the side wall of the riser conduit opposite said inlet opening curving downwardly and laterally to the delivery conduit and forming a continuation of the wall of the delivery conduit, and a helical screw within the delivery conduit constituting the sole means for impelling fuel therethrough and forcing it through the riser conduit, said screw having a reverse vane on its delivery end and being arranged to discharge the fuel laterally from the other.

5. In a fuel conveyer for a locomotive having a firebox, a delivery conduit, a riser conduit having a fuel inlet opening at its lower end and being arranged to direct fuel to a position for its distribution over the firebed in the firebox, said conduits being flexibly jointed in end-to-side relation with one another, the side wall of the riser conduit opposite said inlet opening curving downwardly and laterally to the delivery conduit and forming a continuation of the wall of the delivery conduit, and a helical screw within the delivery conduit constituting the sole means for impelling fuel therethrough and forcing it through the riser conduit, said screw having a reverse vane on its front end and being arranged to discharge the fuel laterally from its underside through said flexible joint from one conduit into the other.

6. In a fuel conveyer for a locomotive having a firebox, a delivery conduit, a riser conduit having a fuel inlet opening at its lower end and being arranged to direct fuel to a position for its distribution over the firebed in the firebox, said conduits being disposed in end-to-side relation with one another, the delivery conduit having an enlargement at its forward end provided with a fuel outlet aperture opening laterally, the side wall of the riser conduit opposite said inlet opening curving downwardly and laterally to the delivery conduit and forming a continuation of the wall of the delivery conduit, and a helical screw within the delivery conduit constituting the sole means for impelling fuel therethrough and forcing it through the riser conduit, said screw having a reverse vane on its front end and being arranged to discharge the fuel laterally through said enlargement from one conduit into the other.

7. In a fuel conveyer for a locomotive having a firebox, a delivery conduit, a riser conduit having a fuel inlet opening at its lower end and being arranged to direct fuel to a position for its distribution over the firebed in the firebox, said conduits being disposed in end-to-side relation with one another, the delivery conduit having an enlarged portion thereon flexibly received by the riser conduit, said enlarged portion being provided with a fuel outlet aperture opening laterally, the side wall of the riser conduit opposite said inlet opening curving downwardly and laterally to the delivery conduit, and a helical screw within the delivery conduit constituting the sole means for impelling fuel therethrough and forcing it through the riser conduit, said screw having a reverse vane on its front end and being arranged to discharge the fuel through said enlarged portion from one conduit into the other, and the greater portion of said fuel outlet apertures being disposed opposite the lower half of said screw.
8. In a fuel conveyer for a locomotive having a firebox, a delivery conduit, a riser conduit having a fuel inlet opening at its lower end and being arranged to direct fuel to a position for its distribution over the firebed in the firebox, said conduits being disposed in end-to-side relation with one another, the side wall of the riser conduit opposite said inlet opening curving downwardly and laterally to the delivery conduit, and a helical screw within the delivery conduit constituting the sole means for impelling fuel therethrough and forcing it through the riser conduit, said screw having a reverse vane of uniform radius on its front end and being arranged to discharge the fuel laterally from its underside from one conduit into the other, and the forward end of the impelling portion of the screw being of increased diameter.
9. In a fuel conveyer for a locomotive having a firebox, a delivery conduit, a riser conduit having a fuel inlet opening at its lower end and being arranged to direct fuel to a position for its distribution over the firebed in the firebox, said conduits being disposed in end-to-side relation with one another, the side wall of the riser conduit opposite said inlet opening curving downwardly and laterally to the delivery conduit, and a helical screw within the delivery conduit constituting the sole means for impelling fuel therethrough and forcing it through the riser conduit, said screw having a reverse vane disposed opposite said inlet opening and being arranged to normally rotate in such direction that the lower portion thereof at the delivery end moves toward said curved side wall.
10. In a fuel conveyer for a locomotive having a firebox, a delivery conduit provided in a side wall thereof with a fuel outlet aperture opening toward one side of the locomotive, a riser conduit having a fuel inlet opening at its lower end and being arranged to direct fuel to a position for its distribution over the firebed in the firebox, said conduits being disposed in end-to-side relation with one another, the side wall of the riser conduit opposite said inlet opening curving downwardly and laterally to the delivery conduit, and a helical screw within the delivery conduit constituting the sole means for impelling fuel therethrough and forcing it through the riser conduit, said screw having a reverse vane on its delivery end opposite said outlet aperture and being arranged to normally rotate in such direction that

the lower portion thereof at the delivery end moves toward said curved side wall to discharge the fuel from its underside and transversely of the locomotive from one conduit into the other.

11. In a fuel conveyer for a locomotive having a firebox, a delivery conduit provided with a fuel outlet opening in a side wall thereof, a riser conduit having a fuel inlet opening at its lower end and being arranged to direct fuel to a position for its distribution over the firebed in the firebox, said conduits being disposed in end-to-side relation with one another, the side wall of the riser conduit opposite said inlet opening curving downwardly to the delivery conduit, and a helical screw within the delivery conduit constituting the sole means for impelling fuel therethrough and forcing it through the riser conduit, said screw having a reverse vane and an additional impelling portion on its front end opposite said outlet opening and being arranged to discharge the fuel from its underside from one conduit into the other.

12. In a fuel conveyer for a locomotive having a firebox, a delivery conduit provided in a side wall thereof with a fuel outlet aperture opening laterally, a riser conduit having a fuel inlet opening at its lower end and being arranged to direct fuel to a position for its distribution over the firebed in the firebox, said conduits communicating with each other and the adjacent ends of said conduits being disposed to one side of the vertical central plane of the locomotive, the side wall of the riser conduit opposite said inlet opening curving downwardly and laterally to the delivery conduit, and a helical screw within the delivery conduit constituting the sole means for impelling fuel therethrough and forcing it through the riser conduit, said screw having an additional impelling portion opposite said outlet aperture arranged to cooperate with the main impelling portion of said screw to sweep the fuel toward the vertical central plane of the locomotive, said screw also being arranged to normally rotate in such direction that the lower portion thereof at the delivery end moves toward said curved side wall.

13. In a fuel conveyer for a locomotive having a firebox, a delivery conduit provided with a front wall and a fuel outlet opening in a side wall thereof rearward of the front wall, a riser conduit opening laterally at its lower end and being arranged to direct fuel to a position for its distribution over the firebed in the firebox, said conduits being disposed in end-to-side relation with one another, the side wall of the riser conduit opposite the lateral opening therein curving downwardly and laterally to the delivery conduit and forming a continuation of the wall of the delivery conduit, and a helical screw within the delivery conduit constituting the sole means for impelling fuel therethrough and forcing it through the riser conduit, said screw having a reverse vane disposed opposite said outlet opening and being arranged to normally rotate in such direction that the lower portion thereof at the delivery end moves toward said curved side wall.

14. In a fuel conveyer for a locomotive having a firebox, a delivery conduit provided with a fuel outlet opening in the lower part of a side wall thereof, a riser conduit opening laterally at its lower end and being arranged to direct fuel to a position for its distribution over the firebed in the firebox, said conduits being disposed in end-to-side relation with one another, the side wall of

the riser conduit opposite the lateral opening therein curving downwardly and laterally to the delivery conduit, and a helical screw within the delivery conduit constituting the sole means for impelling fuel therethrough and forcing it through the riser conduit, said screw having a plurality of reverse vanes and an additional fuel forwarding impelling portion on its front end opposite said outlet opening and being arranged to discharge the fuel laterally from its underside from one conduit into the other.

15. In a fuel conveyer for a locomotive having a firebox, a delivery conduit provided with a fuel outlet opening in a side wall thereof, a riser conduit having a fuel inlet opening at its lower end and being arranged to direct fuel to a position for its distribution over the firebed in the firebox, said conduits being disposed in end-to-side relation with one another, the side wall of the riser 20 conduit opposite said inlet opening curving downwardly and laterally to the delivery conduit, and a helical screw within the delivery conduit constituting the sole means for impelling fuel therethrough and forcing it through the riser conduit, said screw having a reverse vane of uniform radius 25 on its front end opposite said outlet opening, the part of said screw opposite said outlet opening being fixed with respect to longitudinal movement thereof and arranged to discharge the fuel 30 laterally from its underside from one conduit into the other.

16. In a fuel conveyer for a locomotive having a firebox, a delivery conduit provided in a side wall thereof with a fuel outlet aperture opening 35 toward one side of the locomotive, a riser conduit having a fuel inlet opening at its lower end opening toward the other side of the locomotive and being arranged to direct fuel to a position for its distribution over the firebed in the firebox, 40 said conduits communicating with each other and the adjacent ends of said conduits being disposed to one side of a vertical plane through the remote ends thereof, the side wall of the riser conduit opposite said inlet opening extending 45 downwardly and laterally to the delivery conduit and forming a curved continuation of the wall of the delivery conduit, and a helical screw within the delivery conduit constituting the sole means for impelling fuel therethrough and forcing it through the riser conduit, said screw having an additional impelling portion opposite said outlet aperture and being arranged to normally 50 rotate in such direction that the lower portion thereof at the delivery end moves toward said 55 curved side wall.

17. In combination with a firebox having a backhead with a firing opening therethrough, a tubular stoker conduit extending in a general upward and forward direction and at its delivery 60 end communicating with said firing opening, said conduit comprising flexibly jointed conduit sections, the lower rearward section having its bottom inside surface substantially straight along the medial vertical plane thereof, the upper forward section of said conduit constituting an up-

turned delivery portion having a curved side wall, the inside surface of said curved side wall being in concave in transverse cross section and forming in transverse cross section a laterally and upwardly extending continuation of the inside surface of the lower rearward section of said conduit, and a helical screw within the lower rearward section of said conduit constituting the sole means for impelling fuel therethrough and forcing it through said upturned delivery portion, 10 said conduit side wall curving laterally and upwardly in a direction away from the axis of said helical screw.

18. In combination with a locomotive provided with a firebox having a backhead with a firing opening therethrough, a tubular stoker conduit extending in a general upward and forward direction and at its delivery end communicating with said firing opening, said conduit comprising 15 flexibly jointed conduit sections, the lower rearward section of said conduit having its bottom inside surface substantially straight along the medial vertical plane thereof, the forward end of said lower rearward section being disposed to one side of the vertical central plane of the locomotive, the upper forward section of said conduit constituting an upturned delivery portion having a curved side wall, the inside surface of said curved side wall being concave in transverse cross section and forming in transverse cross section a laterally and upwardly extending continuation of the inside surface of the lower rearward section of said conduit, and a helical screw within the lower rearward section of said conduit constituting the sole means for impelling fuel therethrough and forcing it through said upturned delivery portion, 20 said conduit side wall curving laterally and upwardly in a direction away from the axis of said helical screw.

19. In combination with a firebox having a backhead with a firing opening therethrough, a stoker conduit extending in a general upward and forward direction, said conduit comprising a tubular lower rearward portion having its bottom inside surface substantially straight along the medial vertical plane thereof, and a short upturned delivery portion communicating with said firing opening and having a curved side wall, said delivery portion being flexibly connected at its lower end closely adjacent said backhead to the upper forward end of said tubular portion, the inside surface of said curved side wall being concave in transverse cross section and forming in transverse cross section a laterally and upwardly extending continuation of the inside surface of the lower rearward portion of said conduit, and a helical screw within the lower rearward portion of said conduit constituting the sole means for impelling fuel therethrough and forcing it through said upturned delivery portion, 45 said conduit side wall curving laterally and upwardly in a direction away from the axis of said helical screw.

HENRY E. LIPPERT. 65
